UNITED STATES PATENT OFFICE

132,367

DESIGN FOR A COMB

Hiroshi Imamura, Salinas, Calif.

Application October 30, 1941, Serial No. 103,965

Term of patent 3½ years

To all whom it may concern:

Be it known that I, Hiroshi Imamura, a citizen of the United States, residing at Salinas, in the county of Monterey and State of California, have invented a new, original, and ornamental Design for a Comb, of which the following is a specification, reference being had to the accompanying drawing, forming a part thereof.

Figure 3 is also an end view, showing the other end of same; and

Figures 4 and 5 are vertical section views, taken on the lines 4—4 and 5—5 of Figure 1, respectively.

I claim:

The ornamental design for a comb, as shown.

HIROSHI IMAMURA.
